CHECK OUT COUNTER

Edwin F. Schild, 1644 77th Court, Elmwood Park, Ill.

Filed May 19, 1960, Ser. No. 60,655

Term of patent 14 years

(Cl. D80—2)

The dominant features of my design reside in the features shown in full lines.

The portions not shown are substantially plain.

I claim:

The ornamental design for a check out counter, or similar article, as shown and described.
